UNITED STATES PATENT OFFICE

CHARLES LLOYD SLINGERLAND, OF NIAGARA FALLS, ONTARIO, CANADA

WIRE-TYING DEVICE

Application filed October 12, 1929. Serial No. 399,278.

My invention relates to improvements in wire tying devices, and the object of my invention is to construct a hand actuated device which can be manually carried and used for securing the canes of grape vines to the horizontal wires which are generally used for supporting the vines. A further object of my invention is to construct a device that can be operated by one hand which leaves the other hand of the user free to gather the vine canes into place and hold them whilst they are being tied.

My invention consists of a wire tying device constructed and arranged all as herein-after more particularly described and illustrated in the accompanying drawings in which,

Fig. 1 is a side elevational view of my device.

Fig. 2 is an inverted plan view of a fragmentary portion of my device showing the tying wire partially wrapped around the vine.

Fig. 3 is a similar view to Fig. 2 showing the wire tied.

Fig. 4 is a detached perspective view of one of the wire bending levers of my device.

Fig. 5 is a detached perspective view of the other wire bending and cutting member of my device, and

Fig. 6 is a perspective view of a portion of a grape vine cane and supporting wire therefore tied together by a tie wire formed by my device.

Like characters of reference indicate corresponding parts in the different views.

My device comprises a main frame 1 formed at one end thereof with a hand grip 2, the frame being formed with a recess at 40 the end remote from the hand grip 2.

The recess forms in itself a jaw 3 and in the top of such jaw and mounted upon the frame I provide a plate 4 which extends laterally of one side of the frame. The projecting side of the plate 4 is furnished with an orifice 5 and a V-shaped slot 6 extending inwardly from the edge of the plate. The end 7 of such slot is undercut so that it forms a cutting edge.

Underneath the plate 4 I mount a wire

bending and cutting plate 8 which is pivotally mounted upon a pin 9 extending from the plate 4, the plate 8 sliding upon the plate 4.

The plate 8 is formed with a cutting edge 10 and with a recess 11 formed between such cutting edge and the rounded portion of the plate surrounding the pin 9. The edge 10 is so formed upon the plate 8 that as such plate 8 oscillates below the plate 4 the cutting edge 10 moves across the orifice 5 in the plate 4 and the recess 11 moves along the slot 6 in the plate 4 as shall be hereinafter explained.

A finger grip lever 13 is pivotally mounted upon the frame 1, being swingable about a pin 14, the lever 13 being held in resilient spaced relation to the hand grip 2 by a spring 15 which extends between its upper end and the hand grip 2. The upper end of the lever 13 is connected to the rear end of the plate 8 by means of a link 16, and upon reference to the drawings it will be readily seen that the spring 15 will normally retain the hand grip lever 13 away from the hand grip 2 and the plate 8 fully drawn back in the position illustrated in Fig. 2 in which the cutting edge 10 of such plate is clear of the orifice 5 in the plate 4.

17 is a tying wire bending lever adapted to be actuated by the thumb of the operator and pivotally mounted at its forward end to the frame 1 upon a pin 18. The lever 17 is formed with a slot 36 through which the pin 18 extends, such pin being slidable within the slot so that the swinging radius of the forward portion of the lever may be altered to accommodate canes of various sizes. Upon the upper forward portion of the lever I form a recessed portion 19 which is positioned underneath the plate 4, and 20 is a spiral spring 90 extending upwardly from the lever 17 to the wire holder support 21.

Rotatably mounted upon the frame 1 above the jaw 3 is a feed roller 22 the periphery of which is formed with a wire receiving groove, 95 such roller being furnished with a finger and thumb grip 23. 24 is an arm extending upwardly from the frame 1 and carrying a bell crank lever 25 which is pivotally mounted thereon by a pin 26. The inner end of this

lever carries a roller 27 which engages the feed roller 22 and is held in contact therewith by a spiral spring 28 extending from the other end of the bell crank lever to the top 5 of the arm 24. The point of contact of this roller is vertically above the orifice 5 in the plate 4.

Supported above the frame 1 I position a wire reel 29 which is pivotally mounted upon 10 a pin 30 extending from the top of the arm 21.

In Figures 1, 2, 3 and 6 of the drawings a portion of the grape vine cane is indicated by the numeral 31 and a portion of the horizontal supporting wire to which it is tied 15 by the numeral 32.

The operation of my device is as follows:

In using my device the hand grip 2 and lever 13 are held in one hand of the operator 20 and the tie wire 33 is fed downwardly through the orifice 5 so that it extends across the jaw 3, and a sufficient length is fed down by rotating the roller 22 to form a loop and knot about the cane and its supporting wire.

25 The cane 31 and its supporting wire 32 are then held together in the operator's other hand and placed within the jaw 3, the tying wire 33 being pushed inwardly in the jaw and having its free end extending through the 30 notch 34 in the forward end of the lever 17, the grape vine and tying wire lying in the recess 19 in such lever.

The lever 17 is then actuated by the thumb of the operator so that its forward end swings 35 upwardly and moves the free end of the tying wire into the slot 6 in the plate 4. When the tying wire is in this position the lever 13 is pulled towards the hand grip 2 which swings the link 16 forwardly to oscillate the plate 8 40 across the inner face of the plate 4.

During the first operation of this oscillation of the plate 8, the cutting edge 10 moves across the orifice 5 in the plate 4 and cuts the wire at the point where it emerges from this 45 orifice, and during the remainder of the oscillation of such plate 8 the cut end of the partially formed loop lies within the recess 11 of the plate 8 and as this recess moves along the slot 6 in the plate 4 the two ends of the 50 wire are twisted upon each other to form a knot 35, as illustrated in Figure 6. The under-cutting at the end 7 of the slot 6 and the bevelling of the recess 11 in the plate 8 provides a clearance for the ends of the loop 55 during its twisting operation.

The tying operation is then complete and upon releasing the lever 17 and the finger grip lever 13 they both return to their original positions and are ready for a second operation.

From the foregoing description it will be seen that I have constructed a very simple and efficient type of tying device, which can be readily operated and which will save a great deal of time in the tying of grape vines which,

heretofore, has been solely done by the hand.

What I claim as my invention is:

1. In a wire tying machine of the class described, in combination, a main frame comprising a hand grip portion and an open jaw portion, wire holding and feeding means carried by the frame, the frame provided with an orifice communicating with the upper side of the jaw and also provided with an open ended slot adjacent to said orifice, a plate mounted for oscillation against and below the upper face of the jaw, means for oscillating said plate, said plate formed with a cutting element adapted to move across the orifice in the frame and with a recess adapted to move under the slot in the frame as the plate is oscillated, and a movable tying wire bending member extending across the jaw underneath the oscillatable plate.

2. In a wire tying machine of the class described, in combination, a main frame comprising a hand grip portion and an open jaw portion, wire holding and feeding means carried by the frame, the frame provided with an orifice communicating with the upper side of the jaw and also provided with an open ended slot adjacent to said orifice, a plate mounted for oscillation against and below the upper face of the jaw, means for oscillating said plate, said plate formed with a cutting element adapted to move across the orifice in the frame and with a recess adapted to move under the slot in the frame as the plate is oscillated, and an independent manually actuated tying wire bending member swingable across the jaw underneath the oscillatable plate.

3. In a wire tying machine of the class described in combination, a main frame comprising a hand grip portion and an open jaw portion, wire holding and feeding means carried by the frame, a stationary plate fixedly carried by the frame at the upper side of the jaw and projecting laterally to one side of the jaw, the projecting portion of said plate provided with an orifice therethrough and with an open ended slot extending inwardly from the edge of the plate, a second plate mounted for oscillation against the under face of the first plate, means for oscillating the second plate, said plate formed with a cutting element adapted to move across the orifice in the first plate and with a recess adapted to move under the slot in the first plate as the second plate moves under the first plate in its oscillatory movement, and a movable tying wire bending member extending across the jaw underneath the oscillatable member.

4. In a wire tying machine of the class described, in combination, a main frame comprising a hand grip portion and an open jaw portion, wire holding and feeding means carried by the frame, a stationary plate fixedly carried by the frame at the upper side of the jaw and projecting laterally to one side of the 125 130

5 jaw, the projecting portion of said plate provided with an orifice therethrough and with an open ended slot extending inwardly from the edge of the plate, a second plate mounted for oscillation against the under face of the first plate, means for oscillating the second plate, said plate formed with a cutting element adapted to move across the orifice in the first plate and with a recess adapted to move under the slot in the first plate as the second plate moves under the first plate in its oscillatory movement, and an independent manually actuated tying wire bending member swingable across the jaw underneath the oscillatable plate.

10 5. In a wire tying machine of the class described, in combination, a main frame comprising a hand grip portion and an open jaw portion, wire holding and feeding means carried by the frame, a stationary plate fixedly carried by the frame, at the upper side of the jaw and projecting laterally to one side of the jaw, the projecting portion of said plate provided with an orifice therethrough and with an open ended slot extending inwardly from the edge of the plate, a second plate mounted for oscillation against the under face of the first plate, means for oscillating the second plate, said plate formed with a cutting element adapted to move across the orifice in the first plate and with a recess adapted to move under the slot in the first plate as the second plate moves under the first plate in its oscillatory movement, a vertically swingable lever pivotally mounted intermediately of its length upon the side of the frame adjacent to the jaw, and a tying wire receiving and bending member formed upon the front end thereof, said lever having a slot therein whereby the swinging radius of the wire bending member may be altered.
